SOFA OR THE LIKE

Herbert Ritts, P.O. Box 64336, Los Angeles, Calif.

Filed Aug. 18, 1961, Ser. No. 66,405

Term of patent 7 years

(Cl. D15—11)

Fig. 1

I claim:

The ornamental design for a sofa or the like, substantially as shown.
